UNITED STATES PATENT OFFICE.

GEORGE E. NYE, OF PHILADELPHIA, PENNSYLVANIA, ASSIGNOR OF ONE-HALF TO EDWARD TREDICK, OF SAME PLACE.

DESIGN FOR UNDERWEAR.

SPECIFICATION forming part of Design No. 18,496, dated July 31, 1888.

Application filed April 30, 1888. Serial No. 272,396. Term of patent 3½ years.

To all whom it may concern:

Be it known that I, GEORGE E. NYE, residing at Philadelphia, in the county of Philadelphia and State of Pennsylvania, have invented and produced a new and original Design for Surface Configuration for Underwear, of which the following is a specification.

My invention relates specifically to a surface configuration for undershirts, and is fully represented in the accompanying photographic illustration, to which reference is made.

The principal feature of my design is the series of vertical stripes A and B, presenting on the surface a reticulative appearance. The reticulations differ in the adjacent stripes, being, however, alike in the alternate stripes, and of the peculiar conformation shown in the

photograph, those in the stripes A differing in form and being much coarser or more open than in the stripes B, as shown. Both series of stripes are ribbed transversely, as represented.

What I claim is—

The herein-described surface design for an undershirt, comprising the stripes composed, respectively, of fine and coarse reticulations of the configuration shown.

In testimony whereof I hereunto set my hand, this 5th day of January, 1888, in the presence of two attesting witnesses.

GEORGE E. NYE.
